UNITED STATES PATENT OFFICE.

CLARENCE LEO BEST, OF ELMHURST, CALIFORNIA, ASSIGNOR TO C. L. BEST GAS TRACTION COMPANY, OF SAN LEANDRO, CALIFORNIA, A CORPORATION OF CALIFORNIA.

SPROCKET CHAIN.

1,424,442.

Specification of Letters Patent. Patented Aug. 1, 1922.

Application filed July 16, 1920. Serial No. 396,819.

To all whom it may concern:

Be it known that I, CLARENCE LEO BEST, a citizen of the United States, residing at Elmhurst, in the county of Alameda and State of California, have invented certain new and useful Improvements in Sprocket Chains, of which the following is a specification, reference being had therein to the accompanying drawing.

This invention relates to improvements in sprocket chains and especially to chains for endless track devices of traction engines which employ hinge pintles or bearing members constructed as separate parts and secured in openings in the links.

The object of the invention is to provide an improved chain of the type referred to, to provide improved means for securing the separately formed hinge members in the socket openings of the links that will prevent the hinge members from working loose from the links, and that will be adjustable to compensate for hinge members of different sizes in cross section, due to roughness or imperfection in casting or wear, whereby cast metal structures may be employed without the preparatory machine work and grinding usually required, and a more durable construction is afforded with a material saving in the cost of production.

The invention, with other objects and advantages thereof, and the particular construction, combination and arrangement of parts comprising the same will be understood from the hereinafter contained detail description when considered in connection with the accompanying drawings forming part hereof and illustrating one embodiment of the invention.

In the drawings:—

Figure 1 is a transverse section through a chain link constructed in accordance with the present invention, the view being taken from the position occupied by the link in the upper run of the chain.

Figure 2 is a side elevation.

Figure 3 is a top plan view of a stretch of chain, with parts shown in horizontal section.

Figure 4 is a detail horizontal section of one of the struts.

Figure 5 is an end view of the strut.

Figure 6 is a detail end elevation of the strut and wedge member.

Figure 7 is a detail longitudinal section of the wedge member of Fig. 3.

Figure 8 is a detail end elevation of a modified form of wedge member.

Figure 9 is a longitudinal section of the construction illustrated in Fig. 8.

Figure 10 is a detail view illustrating the wedge member of Figs. 11 and 12 applied.

Figure 11 is a detail view of an end portion of one of the side link members illustrating a slightly modified form of strut.

Figure 12 is a detail end elevation of the strut and wedge member illustrated in Fig. 11.

Figure 13 is a detail longitudinal section of the wedge member of Fig. 11.

Fig. 14 is a detail view of an end portion of one of the side link members showing a further modified form of strut.

Referring particularly to Figs. 1 to 9 of the drawings, the construction shown comprises link members, each consisting of spaced side plates 1, 1, between which at one end is a sleeve or tubular block 2 rigidly secured at each of its ends to the side plates, said sleeve or tubular block 2 and the side plates 1, 1, in the present instance, being shown in the form of a single casting, the side plates or members 1, 1 having inward offset portions 1^a and being arranged in the overlapping relation shown, the plates having upper track bars 1^b and apertured lugs 1^c, to which latter are secured tread plates 3 by bolts or other suitable fastenings 4.

Between the two plates at the opposite ends from the location of the sleeve or tubular block 2 is a hinge bearing member 5. The hinge bearing member 5, which in this particular instance is shown circular in cross section, is of a diameter to fit and work within the sleeve or tubular block 2, the latter having a cylindrical inner face to correspond with the cross sectional form of the hinge member 5, the hinge member being rigidly secured at each of its ends to the side plates 1, 1.

The improved means, provided in accordance with the present invention for rigidly securing the separate strut members in the socket openings of the chain links, comprises a wedge member adapted to be arranged in the socket opening between a wall thereof and a wall of the strut or bearing member. The side plates or members 1, 1,

have socket openings 7, said socket openings extending through tubular projecting portions or bosses 8 on the links. The socket openings 7 are of general circular shape to receive the cylindrical end portions of the struts, and the wall of the socket opening at one side is cut away, as shown, (see especially Fig. 3 of the drawings) to receive the wedge member, an inwardly inclined curved wall 7^a being provided at one side of the socket opening.

The wedge member is in the form of a plate part 9, partly circular in cross section and tapering transversely from its central part to its side edges, having curved side faces 9^a, 9^b. The plate part 9 tapers longitudinally, the outer face 9^a of the plate being inclined as shown to the inner face 9^b of the plate, the outer face 9^b being adapted to work upon the inclined wall 7^a of the socket opening, and the inner face 9^b to engage the curved face of the strut. At one end the wedge member has an integral laterally projecting portion 7^b provided with a centrally disposed aperture 7^c, said laterally projecting part 7^b, when the wedge member is placed in position in the socket of the link members, engaging a threaded stem 10 projecting longitudinally from one end of the strut or bearing member 5. The end portions of the struts 5 are shown provided with threaded sockets 5^a in which the threaded stems 10 are adjustably seated. 11 designates a clamp nut on the stem. As will be understood by turning up the nut 11, the same will abut against the laterally projecting part 9^a of the wedge member and force the wedge member transversely of the socket to tightly bind the strut or bearing member against the wall of the socket opening.

The modified construction illustrated in Figs. 8, 9, 10 is substantially the same as that previously described except that the socket openings 12 in the links 13 are provided with a flat inclined wall 14 at one side, and the wedge plate 15 is shaped, as shown, with a flat outer inclined face 15^a to cooperate with the flat inclined wall 13 of the socket opening.

In the modification illustrated in Figs. 11, 12 and 13, the construction of wedge illustrated in Figs. 1 to 7, is shown applied to a modified form of strut or bearing member. In these Figures, 17 designates a portion of one side plate or link member provided with a substantially semicircular shaped socket 17', and 18 designates the strut or bearing member, in this instance the wedge member being located at the side of the strut opposite to the flat bearing face 15' thereof that cooperates with a radially arranged rib 19^a of the tubular sleeve or block 19. The rib 19^a extends to the axis of the sleeve and is tapered, as shown, from a

point near its base to the outer end thereof providing relatively broad bearing faces 19^b at each side, and an intermediate knife-edge bearing 19^c. The strut or bearing member 18 is adapted to work within the sleeve or 70 tubular block 19, and cooperate with the rib 19^a to afford a rolling contact between the parts at the axial center of hinge motion of the links.

The special construction and arrangement 75 of parts hereinbefore described provides simple, efficient means for firmly securing the separate struts or bearing members in the socket openings of the links, preventing rocking or loosening of said struts or bearing members in the links due to change of contact surfaces in the operation of the treads. The securing means is readily adjustable to compensate for struts or bearing members of different sizes in cross section and variation in the size of the socket openings in cast structures, whereby cast metal parts may be employed without the finishing machine work ordinarily required, and a more durable, less expensive chain is 90 provided.

What I claim is:—

1. In a sprocket chain, link members, means for hinging adjacent link members together comprising a pair of cooperating 95 transversely extending bearing members, one on each link, the bearing member of one link being formed as a separate part, and the link having a socket opening in which an end portion of the bearing member seats, 100 a wedge member extending transversely of the link member in the socket opening thereof between a wall of the socket opening and a wall of the bearing member for adjustment longitudinally thereof, means for adjusting the wedge member including a threaded shank projecting longitudinally from one end of the bearing member, said wedge member having a laterally projecting portion at one end, and a nut on the stem 110 adapted to engage said laterally projecting portion.

2. In a sprocket chain, link members, means for hinging adjacent link members together comprising a pair of cooperating 115 transversely extending bearing members, one on each link, the bearing member of one link being formed as a separate part, and the link having a socket opening in which an end portion of the bearing member seats, 120 a wedge member extending transversely of the link member in the socket opening thereof between a wall of the socket opening and a wall of the bearing member for adjustment longitudinally thereof, means for adjusting the wedge member including a threaded shank projecting longitudinally from one end of the bearing member, a nut on the stem adapted to engage the wedge member, said wedge member having a lat- 130

erally projecting apertured part engaging the stem, and a nut on the stem adapted to engage said laterally projecting portion.

3. In a sprocket chain, link members, means for hinging adjacent link members together comprising a pair of cooperating transversely extending bearing members, one on each link, the bearing member of one link being formed as a separate part, and the link having a socket opening in which an end portion of the bearing member seats, a wedge member extending transversely of the link member in the socket opening between a wall thereof and a wall of the bearing member for adjustment longitudinally thereof, and means for adjusting the wedge member including a threaded socket in one end of the bearing member, a threaded stem part adjustably seated in said socket, and a nut on the stem part adapted to engage the wedge member.

4. In a sprocket chain, link members, means for hinging adjacent link members together comprising a pair of cooperating

transversely extending bearing members, one on each link, the bearing member of one link being formed as a separate part and having an end portion circular in cross section, and a link having a socket opening to receive said end portions, said socket opening being of general circular form, the wall of said socket having a recess provided with a curved inclined wall at one side thereof, a segmental shaped wedge plate tapering transversely from its central part toward its side edges, said plate having transversely curved inner and outer faces, and the plate also tapering longitudinally having an outer inclined wall adapted to engage the curved inclined wall of said recess, and means for adjusting said wedge plate.

In testimony whereof I hereunto affix my signature in the presence of two witnesses.

CLARENCE LEO BEST.
